UNITED STATES PATENT OFFICE.

LODEWYCK HOORNBECK, OF NEWARK, NEW JERSEY, ASSIGNOR TO JOHN J. FIELDS, SD,
OF NEW YORK, N. Y.

ELECTRODEPOSITION OF NON-METALLIC BODIES.

1,384,018.

Specification of Letters Patent.

Patented July 5, 1921.

Application filed September 8, 1917. Serial No. 190,316.

To all whom it may concern:

Be it known that I, LODEWYCK HOORNBECK, a citizen of the United States, residing at Newark, in the county of Essex and 5 State of New Jersey, have invented certain new and useful Improvements in Electrodeposition of Non-Metallic Bodies; and I do hereby declare the following to be a full, clear, and exact description of the invention, 10 such as will enable others skilled in the art to which it appertains to make and use the same, reference being had to the accompanying drawings, and to characters of reference marked thereon, which form a part of 15 this specification.

The present invention relates, generally, to a novel means, and method of providing surfaces of non-metallic bodies with a coating or veneer of electrolytically deposited 20 metal, with a view of providing wood or other non-metallic surfaces with a metal-coated or veneered surface which, with the contraction or expansion of the non-metallic body, or with the shrinkage of the body, 25 where improperly seasoned wood is employed for the base, will not bulge or strip from said base.

The present invention therefore has for 30 its principal object, to provide a novel means, in the form of anchoring devices in fixed attachment to said non-metallic body, to which electrolytically deposited metal may attach 35 itself and adhere, for positively and perfectly maintaining the adhesion of the metal surface upon said non-metallic body or base, against bulging, blistering, wrinkling or stripping therefrom.

Other objects of the present invention not at this time more particularly enumerated 40 will be clearly understood from the following detailed description of the invention.

With the various objects of the present invention in view, the said invention consists in the novel application to a non-metallic body or base, of suitable anchoring devices, upon or about which the metal, during the process of electrodeposition, so as to 45 positively and permanently secure the metal coating or veneer against bulging or stripping from the surface of the said non-metallic body or base.

The invention is clearly illustrated in the accompanying drawings, in which:—

Figure 1 is a vertical sectional representation of a non-metallic body or base and

metal coating or veneer secured thereto by means of one style of anchoring devices; and Fig. 2 is a plan or top view of the non-metallic body or base with the anchoring devices shown in said figure, prior to the provision of the surface of the said non-metallic body with the coating or veneer of electrolytically deposited metal.

Fig. 3 is a view similar to that represented in said Fig. 1, but showing the non-metallic body or base and the metal coating or veneer united by means of anchoring devices of a modified construction; and Fig. 4 is a view similar to that represented in said Fig. 2, said view illustrating the plan-arrangement of the non-metallic body or base and the anchoring devices represented in said Fig. 3.

Similar characters of reference are employed in the said above described views, to 75 indicate corresponding parts.

Referring now to Figs. 1 and 2 of the drawings, the reference character 1 indicates a suitable non-metallic body or base, which may be of wood in the form of a 80 plank or other desirable shape, or which may be of any other suitable non-metallic material, fabric or the like. The reference character 2 indicates an application of varnish or suitable sizing for adherence to the 85 wood or other non-metallic body or base 1, and 3 indicates a suitable layer of black lead graphite, copper-bronze, silver leaf, or other like good conductor of electricity, secured to the surface of the said non-metallic 90 body or base by means of the adhering material 2 herein-above mentioned.

Driven into the said body or base 1, through the two layers 2 and 3, as shown in said Fig. 1, are suitably spaced anchoring devices, as 4, the shanks of the said devices in this case being provided with heads or enlargements 5 sufficiently exposed above the upper surface of the said body or base 1, and the layers 2 and 3 thereon, to provide 100 suitable anchoring or retaining means upon or about which portions of the electrolytically deposited metal coating or veneer 3 will be formed and caused to adhere thereto, so as to thoroughly attach itself to the 105 said heads or enlargements in the deposited metal, as will be clearly evident.

The shanks of the said devices 4 are also preferably split, as at 6, so as to provide pointed elements, as 7, which when the said 110

anchoring devices are driven into position in the non-metallic body or base 1, will sufficiently spread apart, as shown, thereby also providing other anchoring or retaining means which will immovably attach said anchoring devices to the body or base 1 and thereby prevent bulging outwardly or stripping of the deposited metal coating or veneer from the non-metallic body or base by reason of any movement of said anchoring devices relative to the latter.

In Figs. 3 and 4 of the drawings, I have illustrated the non-metallic body or base 1 provided with suitably disposed key-receiving slots or grooves, as 9, in which are arranged suitable keys, as 10, of metal, providing a modified construction of anchoring means. As shown in Fig. 3, the said slots or grooves 9 are formed with the undercut retaining surfaces 11 with which the tapered surfaces 12 of the said keys are brought into locked registration, as shown. The said keys have their respective surface-portions 13, which are also tapered or undercut, as shown in said Fig. 3, extending sufficiently above the upper surface of the said body or base 1, and the layers 2 and 3 thereon, to provide suitable anchoring means upon and about which portions of the metal coating or veneer are deposited, so as to thoroughly embed the projecting portions of the said keys in the deposited metal, whereby the latter attaches itself and adheres to said keys.

The reference-characters 14 and 15 indicate the usual circuit wires of an electro-depositing machine or apparatus of any suitable construction.

In carrying out the steps embodying the novel method of providing the surface of a non-metallic body or base with a coating or veneer of electrolytically deposited metal, the surface or surfaces of the said body or base 1 are first painted with the coating of

varnish or sizing 2, and then the layer of 45 electrical conducting material 3 for deposition is applied, the anchoring devices being next secured in their proper and desired locations. The electric circuit-wires 14 and 15 are then properly attached, and the electric current turned on, so that the metal from the anodes of the depositing apparatus will be deposited upon the layer 3 and upon or about the exposed portions of the anchoring devices, as will be clearly evident, and 55 resulting in the product illustrated in Figs. 1 and 3 of the drawings.

Of course it will be evident, that the anchoring devices may be secured in their respective positions upon the non-metallic 60 body or base 1, before the application of the layers 2 and 3 thereto, if desired; and, furthermore, other shapes of anchoring devices may be employed, as will be clearly evident.

I claim:—

As a new article of manufacture, a non-metallic base, an electric conductor, and an adhesive means for causing said conductor to adhere to a surface of said base, anchoring devices connected with said base, each anchoring device comprising a bifurcated shank adapted to be driven into and anchored in said base and an anchoring enlargement extending beyond the surface of said conductor, and a coating of electrically 70 deposited metal upon the face of said conductor, said anchoring enlargements being entirely embedded in and beneath the exposed surface of said electrolytically deposited metal which attaches itself to and 80 adheres to said anchoring enlargements.

In testimony that I claim the invention set forth above I have hereunto set my hand this 6th day of September, 1917.

LODEWYCK HOORNBECK
